UNITED STATES PATENT OFFICE.

MAX KOWINSKY, OF NEW YORK, N. Y.

TOOTH-BRUSH.

1,248,675.

Specification of Letters Patent.

Patented Dec. 4, 1917.

Application filed October 11, 1915, Serial No. 55,256. Renewed October 31, 1917. Serial No. 199,609.

To all whom it may concern:

Be it known that I, MAX KOWINSKY, a subject of the Czar of Russia, residing at New York, in the county of New York and 5 State of New York, have invented new and useful Improvements in Tooth-Brushes, of which the following is a specification.

This invention relates to a tooth brush and has as its principal object to provide 10 such a device which is absolutely sanitary; a further object of the invention is to provide such a device which is simple of construction and comparatively cheap to manufacture and easy to handle; a still further 15 object is to provide a tooth brush adapted for cleaning the teeth both sidewise, in the customary manner, and up and down.

With the foregoing and other objects in view, the invention consists in the particular 20 construction, combination and arrangement of parts more specifically described herein-after and shown in the accompanying drawing, in which:

Figure 1 is a plan view of the holder part 25 of a tooth brush constructed according to my invention.

Fig. 2 is a side elevational view of the same, with the brush parts inserted into the holder and showing, in section, a paper 30 cover or cap on the brush parts.

Figs. 3 and 4 are partly sectional, partly 35 elevational views, on an enlarged scale, of one of the gripping parts of the holder, the sections being taken on the lines 3—3 and 4—4, respectively, looking in the direction indicated by arrows.

Fig. 5 is a perspective view, on a still further enlarged scale, of one of the brush parts 40 detached from the holder, showing a fraction of the paper cap applied to it.

Fig. 6 is a fractional side elevational view of a modified form of the tooth brush, complete, and

Fig. 7 is a plan view of the same, with the 45 brush part removed.

The same part is designated by the same reference character throughout the several views.

Referring more particularly to the drawing, Fig. 1 shows a tooth brush holder made 50 of one piece of rigid material, preferably stamped out of German silver or other inexpensive, non-corrosive metal. It has a handle part 8, a gripping member 9 integrally formed on one end thereof and in alinement 55 therewith, and another similar gripping

member 10 formed on its other end, at right angles thereto. The first one serves for the brushing of the teeth along the rows thereof, from one side of the mouth 60 to the other, in the customary manner, and the second one for brushing them up and down, from the upper gum to the lower one and vice-versa.

The gripping members 9 and 10 are 65 curved so as to conform substantially to the curvature of the gums. They have upwardly converging sides 11 turned at right angles at either extremity, so as to form a box-like structure, one end 12 of which is 70 flush with the sides and the other end 13 is partly cut away.

Fig. 2 shows the holder with brush members 14 inserted into the gripping members 9 and 10. The brush members are curved 75 similarly to the gripping members and fit tightly into same, being somewhat larger and compressed when inserted. They are made of a resilient, porous material, preferably felt and saturated by a special process 80 with a composition which has a disinfecting and deodorizing property. The process of impregnation is such as to make it lasting.

The brush members 14 are shoved into 85 the gripping members 9 and 10 at the ends 13 of the latter and, when they reach the ends 12, they are pushed down by a pressure on the top which is provided with teeth 15. A tissue paper cover or cap 16 is placed on 90 each brush member 14 to protect it from contact with the fingers or other foreign substance during the process of inserting them into the holder. When they are inserted, the cap 16 may easily be removed in 95 an obvious way.

All inside edges and corners of the gripping members are rounded so as to prevent the collection of dust or other foreign matter there and to allow the holder to be easily 100 cleaned. This is one of the important sanitary features of my tooth brush.

It will be obvious from the foregoing that my invention contemplates the use of a new brush member for each cleaning of the teeth, 105 which is the most hygienic procedure and, as the felt pads can be made very cheap, it is also commercially possible.

In the modified form of my device, shown in Figs. 6 and 7, the gripping members 9 110 and 10 and the brush member 14 are straight instead of curved, as some persons with an

abnormal curvature of gums may prefer this form of the brush. Otherwise the construction is the same as that of the brush shown in Figs. 1 to 5.

5. It is also obvious that I may construct a holder with only one of the two gripping members 9 and 10 and may make other alterations or modifications, without departing from the principles of my invention, 10 laid down in the claim hereunto appended.

I claim:

In a tooth brush, a holder formed of one piece of material, having a flat handle portion, a box-like structure on either end of 15 said handle-portion, formed by upturned portions of said material, one of said box-

like structures being in longitudinal alignment with said handle portion and the other of said box-like structures at right angles thereto, both being in the same horizontal 20 plane, said box-like structures being closed at one end entirely and at the other end partially by turned-in portions of said material, substantially as and for the purpose set forth.

25 In testimony whereof, I affix my signature in the presence of two witnesses.

MAX KOWIŃSKY.
